UNITED STATES PATENT OFFICE

AUGUST W. SWENTOR, OF KANSAS CITY, MISSOURI, ASSIGNOR, BY MESNE ASSIGNMENTS, TO OSWEGO FALLS CORPORATION, OF FULTON, NEW YORK, A CORPORATION OF NEW YORK

CAPPING HEAD

Application filed April 14, 1930. Serial No. 444,074.

This invention relates to capping machines and has for its primary object the provision of auxiliary structures to be built into the capping head of the machine which structure will permit the use of caps of the plain type or those having lifting flaps affixed to the face thereof.

This invention relates to capping machines which are especially adapted for use in placing disc shaped caps in the mouths of milk bottles or any similar container adapted to receive and be closed by a disc shaped cap.

It is known in this art that capping machines of the ordinary construction are adapted for feeding plain disc shaped caps or caps having lifting flaps formed therein and lying flush with the surface thereof. The use of caps having stapled-on lifting flaps is precluded by the ordinary structures found in the many capping machines now in use. It is therefore the primary object of this invention to provide means and structure for converting the capping heads of the well known capping machines into devices which will be efficient in handling either plain caps or those provided with lifting flaps which are stapled or otherwise affixed to the cap so that they lie above the surface of the disc. In the capping heads of most capping machines is to be found a passageway which supports the cap in bridged relation to the floor of the passageway. In this, and the usual manner, a portion of the cap is spaced above the floor of the passageway extending between the cap magazine and the delivery throat of the head in a fashion which often-times causes the cap lying directly on the sides of the passageway to tilt out of the plane of the feeding plate so that the edge adjacent the feeding plate will not be engaged thereby when the same is reciprocated to move a cap into place.

With this short-coming in mind and to prevent excessive jamming of the machine, it is the object of this invention to provide a support in the form of a pin which projects upwardly from the floor of the passageway on a diametrical line extending across the cap parallel with the sides of the passageway and adjacent the edge of the cap. This con-

struction, although extremely simple, is highly efficient in rendering capping heads susceptible of using and properly feeding caps of either the plain design or having lifting flaps affixed thereto. In fact, a capping head constructed in accordance with this invention may have alternate supplies of plain and lifting flap equipped discs fed through the magazine without adjustment and with extremely high efficiency.

It is understood that capping heads having shouldered sides along the passageway to permit clearance of projecting lifting flaps have been in use and it is also known that such improvements do not fulfill the requirements of a perfectly operating capping head which is called upon to feed caps provided with lifting flaps which might assume any position around the edge of the cap as it is being fed through the head. With the above broad objects in view and having in mind details of construction which will be clearly set forth during the course of the specification, the invention will now be described with particular reference to the accompanying drawing wherein but the preferred form of the invention has been illustrated and applied to the well known head of a capping machine.

Figure 1 is a side elevation of a capping machine equipped with auxiliary structures in accordance with this invention, parts being broken away for clearness.

Fig. 2 is a horizontal cross section along the line II—II of Fig. 1 showing a cap in position ready to be moved into the passageway by the feed plate.

Fig. 3 is an enlarged detailed fragmentary vertical cross section taken on line III—III of Fig. 2, and,

Fig. 4 is a similar section taken on line IV—IV of Fig. 2.

Like reference characters refer to similar parts throughout the several views and the numeral 6 indicates the magazine of an ordinary capping head which receives disc shaped container caps 8 from a tube of the same as shown in Fig. 1. In the instance shown, and to fully describe the valuable features of this invention, each of the disc

shaped caps 8 is provided with a lifting flap 10 which may be affixed to the cap 8 by a staple or similar affixing means 12. This staple 12 is passed through the lifting flap 10 adjacent the end nearest the edge of cap 8 which allows the free end to be raised to a perpendicular position whereby the flap is used as a lifting element to remove the cap from the bottle 14. The well known feed plate 16 affixed to a reciprocating bracket 18 is used to move the caps 8 from the magazine 6 to the delivery throat 20 through passageway 22 which forms a way between the magazine 6 and delivery throat 20. Feed plate 16 is of a thickness equal to, or a few thousandths of an inch less, than the thickness of the cap 8 and follows the cap through until it drops into a delivery throat 20.

Any suitable actuating mechanism, such as the levers 24, may be used to actuate the feed plate 16 and the plunger arm 26 is reciprocated vertically to force the cap 8 into the mouth of bottle 14 after a cap 8 has been properly delivered into throat 20. This construction and the features mentioned to this point are common in the art and no novelty lies therein so far as this particular invention is concerned, except in a combination way with the hereinafter described parts which are added to the commonly used capping machine. Passageway 22 has each of its sides formed to present a pair of shoulders 28 which are arcuate adjacent their one end as shown in Fig. 2 and which end abruptly at the wall of the delivery throat 20 in a manner which causes a portion of cap 8 to extend across passageway 22 in a bridging fashion. The floor 30 of passageway 22 lies in a plane below the planes of the shoulders 28 and when cap 8 is supported by the shoulders as shown in the drawing, it is extremely desirable to provide a support pin 32 which projects upwardly from floor 30 to engage the lower surface of the lowermost cap 8 in magazine 6. This expedient is vastly important in that support 32 precludes any rocking movement on the part of cap 8 which would raise the periphery thereof to be engaged by feed plate 16 to a point where when the feed plate 16 is actuated it would not properly engage cap 8 and would therefore jam the machine by passing beneath the lowermost cap 8 to force it upwardly against the far edge 34 of magazine 6.

It is not possible to overcome this tendency on the part of the cap 8 to tilt by lifting the level of floor 30 because of the various positions which the staple 12 might take around the periphery of the cap 8 when it is traveling through passageway 22. The head of this pin 32 is dome shaped to allow it to slidably engage the lower surface of the cap 8 and even though the staple 12 would strike the top of pin 32 it would ride thereover without affecting the feeding qualities of the head.

Shoulders 28 are spaced apart sufficiently to clear the turned under ends of staple 12, yet will support the cap 8 on the same plane as feed plate 16 as shown in Fig. 2. It is desirable to have pin 32 positioned intermediate the sides of passageway 22 and adjacent the periphery of the cap 8 on a diametrical line extending parallel to the line of travel and substantially parallel to the sides and shoulders of passageway 22 and 28 respectively.

When altering a capping head in accordance with this invention, it may be desirable to mill in the passageway an additional shoulder 28 as only one is present. The depth of these shoulders may vary slightly, their purpose being to permit clearance of any projecting parts of staples 12 without altering the normal plane of cap 8. The uppermost point of pin 32 should lie in a horizontal plane the same as the horizontal plane of the sides of passageway 22 to insure proper positioning of the caps 8. It is obvious that this pin 32 may be built into the head without a great deal of trouble and the value of the same manifests itself at once to those skilled in the art. As a matter of fact, it has been discovered that the addition of this pin or a similar support renders the capping head positive in its action and absolutely insures proper feeding at all times, regardless of the construction of the cap used.

Having thus described the invention, what is claimed as new and desired to be secured by Letters Patent is:

1. In a capping machine, a cap magazine, a delivery throat, a passageway joining the magazine and throat, a feed plate to successively deliver caps from the magazine to the throat through said way, and a support positioned in the passageway intermediate the sides thereof to slidably engage the lower side of the caps as they are delivered.

2. In a capping machine, a cap magazine, a delivery throat, a passageway joining the magazine and throat, a reciprocating feed plate to successively deliver the caps from the magazine to the throat through said way, shoulders formed along the two sides of said passageway and a support positioned in the passageway intermediate the shoulders thereof to engage the lower side of the caps as they are delivered.

3. In a capping machine, a cap magazine, a delivery throat, a passageway joining the magazine and throat, said passageway having stepped shouldered sides, a floor disposed in a plane below the plane of said shoulders and a pin projecting upwardly from said floor into said passageway intermediate the shouldered sides thereof to engage beneath each cap successively as it is presented to the passageway from said magazine.

4. In a capping machine, a cap magazine, a delivery throat, a passageway joining the

magazine and throat, a floor intermediate the sides of said passageway disposed on a plane below the plane of the sides thereof whereby the caps are held above said floor by said 5 sides and a pin extending upwardly from the floor to engage the lower side of the caps respectively intermediate the cap supporting sides of the passageway.

5. In a capping machine, a cap magazine, 10 a delivery throat, a passageway joining the magazine and throat, a floor intermediate the sides of said passageway disposed on a plane below the plane of the sides thereof whereby the caps are held above said floor by said 15 sides, a pin extending upwardly from the floor to engage the lower side of the caps respectively intermediate the cap supporting sides of the passageway and a dome shaped head formed by the upper end of said pin 20 to permit unobstructed sliding movement by the caps thereover.

6. In a capping machine, a cap magazine, a delivery throat, a passageway joining the magazine and throat, said passageway having 25 sides disposed in a plane above the floor thereof whereby the lowermost cap of the magazine is supported by said sides to bridge the passageway above said floor, a pin engaging beneath said cap at a point adjacent its periphery on a diameter thereof parallel to the 30 sides of said passageway.

7. In a capping machine, a cap magazine, a delivery throat, a passageway joining the magazine and throat, a feed plate to successively deliver caps from the magazine to the 35 throat along said passageway, shoulders formed by the sides of said passageway and the end thereof adjacent said feed plate to support said caps with a portion of their 40 periphery adjacent said delivery throat in bridging relation to the floor of said passageway and a pin engaging beneath said bridging cap intermediate the sides of said passageway between feed magazine and delivery 45 throat whereby tilting of the cap downwardly into the passageway at the bridging portion of the periphery thereof is precluded.

8. In a capping machine for the application of disc-shaped bottle caps, a cap magazine to carry a vertical stack of said caps, a 50 delivery throat to receive a portion of the bottle being capped, a reciprocating feed plate to successively deliver caps from the magazine to the throat along said passageway, continuous shoulders formed by the two opposite sides of said passageway and the one end thereof adjacent said delivery throat to support said caps with a portion of their 55 periphery adjacent said delivery throat in bridging relation to the floor of said passageway, and an upstanding vertical pin, having 60 a dome-shaped end, engaging beneath said bridging cap intermediate the sides of said passageway between the feed magazine and 65 delivery throat and intermediate the shoul-

dered sides thereof to preclude tipping of said cap downwardly into the passageway toward the floor thereof.

In testimony whereof, I hereunto affix my 70 signature.

AUGUST W. SWENTOR.
